DEEP WELL PUMP

George F. Wislicenus, Summit, N. J., assignor to
Worthington Pump and Machinery Corporation,
Harrison, N. J., a corporation of Delaware

Application March 2, 1944, Serial No. 524,710

8 Claims.

(Cl. 103—102)

This invention relates to centrifugal machines such as deep well and sump pumps, and more particularly to a novel casing and rotor structure.

An object of the present invention is to provide a centrifugal machine of the multistage type in which the casing and rotor thereof are of such design as to permit axial removal of the rotor intact from the casing without necessitating separation of the casing.

Another object is to provide a centrifugal machine of the multistage type wherein both the casing and the rotor may respectively comprise a unitary structure, and in which the rotor may be axially removed intact from the casing without necessitating dismantling of the rotor or separation of the casing.

Another object is to provide a deep well pump of the multistage type which is of such design as to eliminate the necessity of a large number of bearings for supporting the rotor in the casing.

Another object is to provide a centrifugal machine of the multistage type having a rotor provided with fluid deflecting vanes coacting with the body structure of the rotor in such manner as to function as strut means for resisting deflection of the rotor.

Another object is to provide a casing and a rotor for a centrifugal machine of the multistage type in which the construction is such that the running joints of both parts may be machined in one setting to automatically assure alignment.

A further object is to provide a centrifugal machine of the multistage type wherein mechanically the structure is characterized by a simplification in design comparable to that of a single stage machine.

With these and other objects in view, as may appear from the accompanying specification, the invention consists of various features of construction and combination of parts, which will be first described in connection with the accompanying drawing, showing a deep well pump of a preferred form embodying the invention, and the features forming the invention will be specifically pointed out in the claims.

In the drawing:

Figure 1 is a longitudinal sectional view of a deep well pump in accordance with the present invention.

Figure 2 is a longitudinal sectional and elevational view of a modified form of pump structure.

Referring more particularly to the drawing, Figure 1 illustrates a deep well pump comprising a casing 10 within which is contained a rotor 11. The casing 10 comprises a series of identical stage

bowls or sections 12, a bottom end section 13 and a discharge cone or top end section 14, all of which are arranged end to end. Bolts 15 extend through flanges 16 on the bowls 12, the section 13 and the discharge cone 14 for connecting the parts into a unitary structure. The section 13 is internally threaded at 16 for connection with the usual strainer (not shown), and the discharge cone 14 is threaded at 17 with the usual drop pipe 18. While Figure 1 illustrates a five stage centrifugal machine, the number of stages will depend entirely on the specific type of service for which the pump is designed. Since the bowls 12 are of like construction, the casing 10 may be built in any number of stages by merely assembling and securing together the requisite number of bowls.

All the bowls 12 and the discharge cone 14 have inner faces 19 arranged concentrically of the axis 20 of the casing 10 and extending 360 degrees thereabout. These faces are of curved or concaved contours when viewed according to Figure 1. Inside the respective bowls 12 and the discharge cone 14 are mounted wearing or shroud rings 21 which are arranged in co-axial relationship at the axis of the casing 10. The wearing rings are of smaller outside diameters than the inside diameters of the bowls 12 and the discharge cone 14 and have curved or convexed outer faces 21 spaced from the faces 19 to provide stage fluid passages 22.

As will be noted by reference to Figure 1, the fluid passages 22 are curved or generally U-shaped in cross section and have fluid inlets 23 and fluid outlets 24 opening through the inside annular contour of the casing for communication with the rotor containing chamber of the casing. Means for supporting the wearing rings 21 comprise guide vanes 25 which are arranged in the respective fluid passages 22 and are integral with the wearing rings and the bowls 12 and the discharge cone 14.

To the bottom end of the rotor 11 is attached a co-axial shaft 26 which is supported for rotation in a bearing 27. This bearing is arranged concentrically with and inside the end section 13 and is of smaller outside diameter than the inside diameter of the section 13 to define a fluid passage 28 which is annular in cross-section. Inlet guide vanes 29 provide support for the bearing 27, these vanes being integral with the bearing and the end section 13. The bearing 27 is externally contoured to present a smooth surface to the fluid stream flowing through the passage 28.

Additional support is provided for the rotor 11 by a second bearing 30 mounted in an inner cone 31 which is fixedly related to the discharge cone 14 by guide vanes 32. The vanes 32 are integral with the inner cone 31 and a ring 33 attached to the discharge cone 14. The upper end of the rotor 11 is attached to the usual drive shaft 34. The shaft 34 is co-axial with the shaft 26 and is supported for rotation in the bearing 30. The shaft 34 extends upwardly to any approved type of driving head (not shown) and may be connected with any suitable source of power.

The inner cone 31 is of smaller diameter than the discharge cone 14 to provide a fluid passage 15 which places the last stage fluid passage 22 in communication with the drop pipe 18.

Specifically the rotor 11 comprises a series of stage impellers 36 arranged end to end and fixedly connected one with the other. The first stage impeller 36 includes an end body 37 having a bore 38 within which is secured the shaft 26. A shroud ring 39 is spaced axially from the body 37 to provide a fluid passage 40 which extends 360 degrees about the axis of the rotor 11. The eye 41 of the first stage impeller 36 communicates with the annular passage 28, and the fluid passage 40 discharges into the inlet 23 of the first stage fluid passage 22. Fluid deflecting vanes 42 are arranged in the passage 40 and are integral with the body 37 and the shroud ring 39 to connect the parts into a unitary structure.

The remaining impellers 36 respectively comprise hollow bodies 43 which are open at their ends and annular in cross-section. An annular flange 44 is formed on the end body 37, within which is inserted an end of the second stage body 43. Bolts 45 fixedly connect the end body 37 with the second stage body 43. The third, fourth, and fifth stage bodies 43 are fitted inside annular flanges 46 on the second, third, and fourth stage bodies 43, respectively, and the abutting bodies are fixedly related one with the other by bolts 47.

All the bodies 43 are constricted intermediate their ends so that, because of the spool-like contours of the bodies, each body is characterized by a channel or groove 48 extending circumferentially 360 degrees about the body. Shroud rings 49 encircle the respective bodies 43 and are spaced from the faces of the bodies defining the channels 48 to provide fluid passages 50 extending circumferentially 360 degrees about the axis of the rotor 11. The inner faces 51 of the shroud rings are convexed in cross-section and are curved in conformity with the curvature of the channels 48 so that the fluid passages 50 are of curved or generally U-shaped contour in cross-section. Thus the respective fluid passages 50 have inlets 52 and outlets 53 opening through the annular perimeter of the rotor. The inlets 52 and outlets 53 are arranged in communication with the outlets 24 and the inlets 23, respectively so that the fluid passages 50 are in series communication with the fluid passages 22.

Means for supporting the shroud rings 49 comprise fluid deflecting vanes 54 arranged in the respective fluid passages 50. These vanes are integral with the bodies 43 and the shroud rings 49 and are of the combination inward flow and outward flow type, such as are disclosed in an application for patent on Rotor filed on even date herewith. Accordingly, the vanes 54 extend from end to end of the respective passages 50.

Provision of the vanes 54, particularly the por-

tions thereof which lie in the inlets 52 and the outlets 53, make the rotor 11 very bending-stiff without depending in any way on shaft stiffness, since the vanes form a continuous mechanical structure of large diameter. Thus the vanes 54 function additionally as strut means co-acting with the impeller bodies 43 and the shroud rings 49 to resist deflection of the rotor. With this form of construction, a central shaft becomes actually unnecessary, the shafts 26 and 34 being employed for bearing purposes only, in addition to the driving function of the shaft 34.

The end body 37 and the bodies 43 are respectively provided with wearing surfaces 55 of a common diameter. The wearing surfaces 55 lie in the planes of and in co-active relationship with the wearing surfaces or inner faces 56 of the wearing rings 20. All the wearing surfaces 56 are also of a common diameter. Similarly, the shroud rings 49 and the shroud ring 39 are provided with wearing rings 57 having the same outside diameter as the wearing surfaces 55. All the wearing rings 57 lie in the planes of and in co-active relationship with the respective wearing surfaces 58 comprising the inner faces of necks 59 to which the flanges 16 are attached. The wearing surfaces 58 are of the same diameter as the wearing surfaces 56.

The wearing surfaces 55 and the wearing rings 57 are of diameters at least equal to the outside diameters of the respective impellers 36, and the wearing surfaces 58 and 60 constitute the smallest inside diameter of the casing. Accordingly the rotor 11 may be axially removed intact from the casing 10 without removing or opening any stationary parts except the inner cone 31, or the end section 13 if the rotor is removed through the upper end of the casing. The casing 10, which contains all the stationary passages, need not be parted either in the plane of or at right angles to its axis. In addition, the running joints in the casing as well as on the rotor can be machined in one setting to automatically assure perfect alignment. The rotor may also be dynamically balanced as a whole. The machine herein described is completely devoid of any stationary parts which reach between the impellers of the individual stages.

The shroud ring 21 in the discharge cone 14 differs somewhat from the remaining shroud rings 21, in that this shroud ring is provided with a wearing ring 60 of considerable length, and the wearing surface 55 associated with this ring is also of a greater length than the remaining wearing surfaces 55. This wearing ring fits over the base end of the inner cone 31. An end body 61 is fitted inside the flanges 44 on the last stage body 43 and is secured thereto by bolts 62. A bushing 63 is mounted on the shaft 34 inside the bearing 30 and is interposed between the end body 61 and an annular shoulder 64 on the shaft 34, the latter extending through a bore 65 in the end body. A nut 66 is threaded on the shaft 34 and bears against the end body 61 to clamp the bushing 63 between the end body and the annular shoulder 64.

While Figure 1 illustrates both the casing 10 and the rotor 11 as being of sectional construction, Figure 2 illustrates a centrifugal machine wherein the casing 10 and the rotor 11 are respectively of unit construction. In other respects the two pump structures are identical so that similar reference characters are applied to corresponding parts, with the exception that the reference characters are primed in Figure 2. Although the axi-

ally removable rotor permits the use of a one-piece casing, there are certain advantages in building up the casing from individual and small castings. Such advantages reside in the simplification of foundry problems and low pattern costs. This type of construction also facilitates cleaning of the fluid passages, and the exact stage distances are assured by pre-machining the individual casing pieces before assembling the pieces into a finished casing structure. Final machining of the casing is done after the casing pieces have been connected together.

In both forms of the device, the respective fluid passages in the casing part extend 360 degrees about the axis of that part and are curved inwardly to place their ends in communication with the rotor chamber. Similarly, the fluid passages in the rotor part respectively extend 360 degrees about the axis of the rotor and are curved outwardly to open through the annular perimeter of the rotor. The fluid passages in the rotor and the casing are in endwise and series communication one with the other to provide a continuous passage extending from the suction inlet 28 to the discharge 35 of the machine.

Because of the reversed curvature of the casing passages with respect to the rotor passages, the continuous passage is of sinuous contour in longitudinal section, but annular in cross-section. While the continuous passage is wavy, i. e., winding in and out with respect to both the rotor and the casing, the running clearances between the rotor and the casing are so arranged as to isolate the rotor passages one from the other, which is also true of the casing passages, but effectively connect the rotor passages with the casing passages, in addition to permitting unobstructed axial removal of the rotor.

It will be understood that the invention is not to be limited to the specific construction or arrangement of parts shown, but that they may be widely modified within the invention defined by the claims.

What is claimed is:

1. In a deep well pump, the combination of a casing having a rotor chamber and annular and axially spaced stage fluid passages each having endwise communication only with said chamber, a rotor in said chamber and having annular and axially spaced stage fluid passages each opening endwise only through the annular perimeter of the rotor, said casing and rotor fluid passages having endwise and series communication one with the other to provide a continuous fluid passage extending from the first stage through the latter stage of the pump, fluid deflecting vanes in said second mentioned fluid passages, said casing comprising connected undivided bowl portions each containing one of said casing fluid passages, and said rotor comprising connected undivided impeller bodies each containing one of said rotor fluid passages.

2. In a deep well pump, the combination of a casing having a rotor chamber and annular and axially spaced stage fluid passages each having endwise communication only with said chamber, a rotor in said chamber and having annular and axially spaced stage fluid passages each opening endwise only through the annular perimeter of the rotor, said casing and rotor fluid passages having endwise and series communication one with the other to provide a continuous fluid passage extending from the first stage through the latter stage of the pump, fluid deflecting vanes in said second-mentioned

fluid passages, said casing comprising connected undivided bowl portions each containing one of said casing fluid passages, said rotor comprising connected undivided impeller bodies each containing one of said rotor fluid passages, said casing having a discharge cone, a cone shaped bearing fixedly related to said casing and spaced therefrom to provide an annular fluid discharging passage between the discharge cone and the cone shaped bearing, and a shaft fixed to said impeller and extending through said cone shaped bearing.

3. In a deep well pump, the combination of a casing having a rotor chamber and annular and axially spaced stage fluid passages each having endwise communication only with said chamber, a rotor in said chamber and having annular and axially spaced stage fluid passages each opening endwise only through the annular perimeter of the rotor, said casing and rotor fluid passages having endwise and series communication one with the other to provide a continuous fluid passage extending from the first stage through the latter stage of the pump, fluid deflecting vanes in said second-mentioned fluid passages, said casing comprising connected undivided bowl portions each containing one of said casing fluid passages, said rotor comprising connected undivided impeller bodies each containing one of said rotor fluid passages, said casing having a discharge cone, a cone shaped bearing fixedly related to said casing and spaced therefrom to provide an annular fluid discharging passage between the discharge cone and the cone shaped bearing, a shaft fixed to said impeller and extending through said cone shaped bearing, a second bearing fixedly related to said casing and spaced therefrom to provide a fluid inlet passage annular in cross section, a head fixed to said rotor, and a shaft attached to said head and rotatably supported in said second bearing.

4. In a centrifugal deep well pump, the combination of a casing provided with a suction inlet and a discharge, said casing having a rotor chamber and axially spaced annular faces arranged concentrically of the axis of said chamber, said annular faces being concaved in cross section, casing shroud rings having convexed faces spaced from the respective annular faces to provide stage fluid passages curved for endwise communication only with said chamber, guide vanes in said fluid passages and fixedly relating the casing shroud rings to said casing, a rotor in said chamber and having channels extending circumferentially of the rotor and being concaved in cross section, rotor shroud rings having convexed faces spaced from the faces of said channels to provide stage fluid passages curved to open endwise only through the annular perimeter of the rotor, fluid deflecting vanes in said rotor fluid passages and fixedly relating the rotor shroud rings to said rotor, said casing fluid passages being reversely curved with respect to said rotor fluid passages and having endwise and series communication therewith to provide a continuous passage sinuous in longitudinal section and extending from said suction inlet to said discharge, said casing shroud rings and rotor shroud rings having wearing surfaces, wearing surfaces on said rotor arranged in co-active relationship with the wearing faces on said casing shroud rings, wearing faces on said casing arranged in co-active relationship with the wearing faces on said rotor shroud rings, said rotor being of such contour with respect to the contour of said chamber as to be axially removable therefrom while in assembled

condition, said casing comprising undivided bowls joined one with the other in the respective planes of the rotor shroud rings.

5. In a centrifugal deep well pump, the combination of a casing provided with a suction inlet and a discharge, said casing having a rotor chamber and axially spaced annular faces arranged concentrically of the axis of said chamber, said annular faces being concaved in cross section, casing shroud rings having convexed faces spaced from the respective annular faces to provide stage fluid passages curved for endwise communication only with said chamber, guide vanes in said fluid passages and fixedly relating the casing shroud rings to said casing, a rotor in said chamber and having channels extending circumferentially of the rotor and being concaved in cross section, rotor shroud rings having convexed faces spaced from the faces of said channels to provide stage fluid passages curved to open endwise only through the annular perimeter of the rotor, fluid deflecting vanes in said rotor fluid passages and fixedly relating the rotor shroud rings to said rotor, said casing fluid passages being reversely curved with respect to said rotor fluid passages and having endwise and series communication therewith to provide a continuous passage sinuous in longitudinal section and extending from said suction inlet to said discharge, said casing shroud rings and rotor shroud rings having wearing surfaces, wearing surfaces on said rotor arranged in co-active relationship with the wearing faces on said casing shroud rings, wearing faces on said casing arranged in co-active relationship with the wearing faces on said rotor shroud rings, said rotor being of such contour with respect to the contour of said chamber as to be axially removable therefrom while in assembled condition, said casing comprising undivided bowls joined one with the other in the respective planes of the rotor shroud rings, said rotor comprising undivided impellers of spool-like contour and joined one with the other in endwise relationship in the respective planes of said casing shroud rings.

6. In a centrifugal deep well pump, the combination of a casing having a rotor chamber and annular and axially spaced stage fluid passages each having endwise communication only with said chamber, a rotor in said chamber and having annular and axially spaced stage fluid pas-

10 sages each opening endwise only through the annular perimeter of the rotor, said casing fluid passages and rotor fluid passages having endwise and series communication one with the other to provide a continuous fluid passage extending from the first stage through the last stage of the pump, guide vanes in said casing fluid passages and extending substantially from end to end of their respective passages, fluid deflecting vanes in said rotor fluid passages and extending substantially from end to end of their respective passages.

15 7. In a centrifugal deep well pump, the combination of a casing having a rotor chamber and annular and axially spaced stage fluid passages each having endwise communication only with said chamber, a rotor in said chamber and having annular and axially spaced stage fluid passages each opening endwise only through the annular perimeter of the rotor, said casing fluid passages and rotor fluid passages having endwise and series communication one with the other to provide a continuous fluid passage extending from the first stage through the second stage of the pump, fluid deflecting vanes in said rotor fluid passages and extending substantially from end to end of their respective passages, said rotor comprising undivided spool-like bodies arranged end to end, means for connecting said bodies into a unitary structure, each of said bodies containing one of said rotor fluid passages, and said rotor being of such contour with respect to the contour of said chamber as to be axially removable therefrom while in assembled condition.

20 8. In a centrifugal deep well pump, the combination of a plurality of individual spool-shaped impellers detachably connected in end to end engagement, each of said spool-shaped impellers having a plurality of generally longitudinally extending curved vanes lying in its concaved contour, a casing surrounding said spool-shaped impellers and comprising individual sections connected in endwise relationship and having surfaces curved reversely to the concaved contours of the spool-shaped impellers, the curved portions of said sections spanning the connection joints of two adjacent spool shaped impellers, the endmost spool shaped impellers in the assembly having shaft receiving heads detachably connected thereto.

GEORGE F. WISLICENUS.
